364, *Castrovilli & Co.*

UNITED STATES PATENT OFFICE.

LEON R. PAUL, OF CHICAGO, ILLINOIS.

FLOOR FORM.

Application filed July 22, 1924. Serial No. 727,564.

To all whom it may concern:

Be it known that I, LEON R. PAUL, a citizen of the United States, residing at Chicago, in the county of Cook and State of Illinois, have invented a new and useful Floor Form, of which the following is a specification.

By way of explanation, it may be stated that the inverted U-shaped or trough-like forms which are used in the making of concrete floors, generally are nailed to the supports which carry the forms. The result is that skilled labor is required to place and displace the forms, and that, notwithstanding the exercise of skill, the forms are bent, distorted and damaged when they are detached from the supports or transportation to another job.

In view of the foregoing, this invention aims to provide a floor form which can be placed by unskilled labor and without nailing, novel means being provided for supporting the form members, and for interlocking them.

It is within the province of the disclosure to improve generally and to enhance the utility of devices of that type to which the invention appertains.

Although preferred forms have been shown, a mechanic, working within the scope of what is claimed, may make alterations without departing from the spirit of the invention.

In the accompanying drawings:—Figure 1 shows in section, a concrete floor, supported by devices constructed in accordance with the invention; Figure 2 is a longitudinal section showing several forms interlocked; Figure 3 is a perspective showing a plurality of interlocked forms, parts being broken away; Figure 4 is a perspective showing one of the terminal forms; Figure 5 is a transverse section showing the form carried by its supports.

In Figures 1, 2 and 3, there is shown an inverted trough-shaped metal form 1 comprising a top 2 and depending sides 3, the sides 3 being bent upon themselves to form outstanding double wall flanges 4 and depending wings 5, the flanges 4 and the wings 5 being cut away as at 6, at one end 7 of the form, so that the end 7 of one form may

be inserted into the opposite end 8 of an adjoining form, as disclosed in Figures 2 and 3, the top 2 of each form being provided with longitudinal slits 9 forming tongues 10, and notches 11, the notch in one form being adapted to receive the tongue 10 of an adjoining form, and the tongues 10 being overlapped on each other as shown best at 12 in Figure 2.

In practical operation, the wings 5 engage the inner edges of the supports 14, as shown in Figure 1, and the flanges 4 rest on the supports, the forms thus being held in place without nailing, no skilled labor being required in assembling or taking down the forms, and the forms being subject to no particular damage, as is the case when the forms 1 are nailed to the supports 14.

The end forms of each line may be constructed as shown in Figure 4, the top appearing at 15, the sides at 16, the wings at 17 and the flanges at 18. In the inner end of the top 15 of the form, the slits 19 and the tongue 20 are fashioned. The modification consists in omitting the tongues 20 and the slits 19 at the outer end 21 of the form, that end of the form being tapered as at 22, the flanges 18 and the wings 17 continuing to the end 21 of the form, instead of being cut away as shown at 6 in Figure 3.

In Figure 5, the supports appear at 23 and the form at 24, the top of the form being designated by the numeral 25 and the sides by the numeral 26. In this form of the invention, the sides 26 are folded upon themselves to fashion double walled depending wings 27, and single layer outstanding flanges 28, the parts 27 and 28 cooperating with the supports 23 in a way which will be understood readily when Figure 5 is noted.

What is claimed is:—

1. A form of the class described, comprising a top, and sides having outstanding flanges and depending wings, the flanges and the wings being cut away at one end of the form, the top of the form being provided, at each end of the form, with longitudinal slits defining longitudinal tongues.

2. A form of the class described, comprising a top, and sides having outstanding flanges and depending wings, the top of the form being provided, at one end of the form,

with longitudinal slits defining a longitudinal tongue.

3. A form of the class described, comprising a top and sides, the sides being bent upon themselves to form cooperating elements comprising outstanding flanges and depending wings, one of said cooperating

elements being of integral, double-walled construction.

In testimony that I claim the foregoing ¹⁰ as my own, I have hereto affixed my signature.

LEON R. PAUL.
